PERCY R. BETTISON, OF NEWARK, NEW JERSEY, ASSIGNOR TO AMERICAN HAIR & FELT COMPANY, OF CHICAGO, ILLINOIS, A CORPORATION OF DELAWARE

FLOOR COVERING AND METHOD OF FORMING THE SAME

Application filed April 27, 1928. Serial No. 273,260.

The invention relates to floor covering and to a method of making the same.

The usual linoleum or cork composition floor covering is relatively hard and unyielding and is generally laid on hard surfaced flooring, such as wood or cement. The object of this invention is to provide a floor covering in which the linoleum or cork carpet is associated with an under cushion of felt, 10 preferably a punched felt having a burlap reinforce with which the feltable fibres are intimately associated, said floor covering being formed by cementing the punch felt to the hard floor and then cementing the linoleum 15 or cork carpet to the punched felt cushion.

The invention further consists in the several features hereinafter described and more particularly defined by claims at the conclusion hereof.

20 The drawing shows a perspective view of the floor covering embodying the invention, parts being shown in section.

In the drawing the numeral 2 designates the hard surfaced under-flooring, here shown 25 as of wood though it may be of cementitious composition, and 3 the linoleum or cork floor covering, which includes a layer 4 of linoleum mastic, usually ground cork or wood-meal secured together by a suitable cement, 30 such as linoxin or its substitutes, laid upon a fabric base 5.

The cushioning material 6 consists of a bat 7 of feltable fibres, preferably animal hair, which are punch felted together and to a 35 fabric reinforce 8, preferably burlap, some of the fibres extending through the meshes of the burlap.

This cushioning material 6 is first laid over the hard flooring 2 and secured thereto by a 40 suitable adhesive spread upon said flooring 2 or upon one side of said material and then linoleum or cork floor covering is laid upon the top surface of said cushion layer 6 and is secured thereto by a suitable adhesive 45 spread upon the bottom face of the floor covering or upon the top side of the cushioning material. The cushioning material is preferably laid with the burlap reinforce 8 uppermost.

With flooring made as above described, the

disadvantage of the hard, unyielding character of the under-flooring and top covering are eliminated by the punch felt cushion interposed therebetween.

I desire it to be understood that this invention is not to be limited to any particular form or arrangement of parts except insofar as such limitations are included in the claims.

What I claim as my invention is:

1. The combination with a hard surface flooring, of a cushioning layer of feltable fibres having a considerable proportion of the fibres arranged to extend substantially normal to the plane of said layer and interlocking the fibres together and providing protruding fibres cemented to said flooring, and a floor covering of linoleum or the like cemented to said cushioning layer.

2. In a floor, the combination with a hard surfaced base, of a layer of cement on said base, a cushioning layer of feltable fibres and a fibrous reinforce on one side, a considerable proportion of fibres arranged to extend transversely through said reinforce and normal to the plane of said layer and interlocking the fibres together and to said reinforce with some of the fibres protruding from said reinforce, said cushioning layer having its plain side in adhesive contact with said cement, a layer of cement on the reinforced side of said cushioning layer, and a surface of linoleum or similar composition flooring upon said last-named layer of cement.

3. In a floor, the combination with a hard surfaced base, of a layer of cement on said base, a layer of needle felt consisting principally of animal hairs interlaced together and to a penetrable fibrous reinforce on one side to dispose a considerable proportion of the fibres normal to the surfaces of said layer and provide protruding fibres and having its plain side in adhesive contact with said cement, a layer of cement on the reinforced side of said felt, and a surface of linoleum or similar composition flooring upon said last-named layer of cement.

In testimony whereof, I affix my signature.

PERCY R. BETTISON. 100
